UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

LINE-SPACING MECHANISM FOR TYPE-WRITING MACHINES.

1,196,110.

Specification of Letters Patent. Patented Aug. 29, 1916.

Application filed April 13, 1916. Serial No. 90,867.

To all whom it may concern:

Be it known that I, EDWARD B. HESS, a citizen of the United States, residing in Brooklyn, in the county of Kings and State 5 of New York, have invented certain new and useful Improvements in Line-Spacing Mechanism for Type-Writing Machines, of which the following is a specification.

This invention relates to the line spacing 10 mechanism of typewriting machines and particularly to mechanism of the kind constructed to turn the platen step by step, by means of pawl and ratchet devices, uniform distances to produce uniformly spaced lines 15 of print and which is associated with means for disengaging the platen from its ratchet mechanism whereby the platen may be turned and adjusted a definite extent for what is called minute fractional spacing between 20 the usual lines for the purpose of printing at a specific diminutive distance intermediate the usual line space wheel ratchet spacing. It is important that the release mechanism, while being simple in 25 construction, should also be easily operated, that it should normally connect the ratchet mechanism securely with the platen and that after a release has been effected and the connection between the platen and the ratchet 30 mechanism is again made, it should be done quickly and securely as soon as the release mechanism returns to its normal position. It is also of great importance that after a release and after a fractional adjustment 35 has been effected and the release mechanism is allowed to return to its normal position that it should do so without turning the platen any appreciable distance in such manner as to disturb the carefully made adjustment which is often produced for the purpose 40 of effecting printing on paper so ruled that accurate adjustment by the ordinary ratchet mechanism cannot be accomplished.

According to my invention the platen is 45 provided with mechanism for line spacing which may be of any well known or suitable kind and in connection with the usual ratchet wheel thereof I employ a locking device of novel construction, one member of which is 50 fixed to, or rigidly connected with, the ratchet wheel and is free to turn therewith on the platen shaft when released from the platen, while the other locking member is arranged to turn with the platen, is slidably mounted on the platen end and is adapted to 55 engage the first-mentioned member of the locking means in such manner that when the ratchet wheel is actuated the platen will be correspondingly turned. That member of the locking means which is secured to the 60 ratchet wheel is preferably cup-shaped and is provided with an annular series of fine teeth or ridges on the inside of its rim while the companion locking member, which is connected to turn with the platen, is prefer- 65 ably in the form of a circular plate or disk having laterally projecting flanges formed with serrations or fine teeth or ridges adapt- 70 ed to engage the annular series of ridges on the cup-shaped member of the locking 75 means. The locking disk normally engages the cup-shaped member being so held by springs housed in the adjacent end of the platen. The locking device may be opened by means of a rod operated by a push but- 80 ton and extending through a channel or bore in the platen shaft and engaging the disk or plate.

In the accompanying drawings Figure 1 is a detail view in front elevation, and with 80 parts broken away, of a typewriter platen with my improved line spacing mechanism applied, showing how the platen is locked to the ratchet mechanism; Fig. 2 shows an end elevation of the end plate or head at one end, 85 of the platen; Fig. 3 shows an end elevation of the disk member of the locking device and it also shows its relation with the outer boss of the end plate and the platen shaft which are shown in section; Fig. 4 shows a side 90 elevation of one end of the platen shaft; Fig. 5, an end view thereof; Fig. 6 shows a side elevation of one end of the platen with my improvements applied, such improved line spacing mechanism being mainly shown 95 in section; Fig. 7 is a detail view on an enlarged scale illustrating how the locking members engage each other. Fig. 8, an enlarged detail view in section, showing the form of the teeth or ridges employed in the 100

locking mechanism; Fig. 9, a side elevation of line spacing mechanism and detent mechanism in connection with which my improved fractional spacing mechanism may be used.

- The platen A may be made in the usual way as by covering a wooden hollow core *a* with a sheathing of rubber or other suitable material *a'* and is secured to the platen 10 shaft C by locking screw Y in the usual way and the platen shaft, and consequently the platen, always revolve or turn together. The end of the platen shown, and to which my improvements are applied, is closed by 15 an end plate or head B having an inwardly extending hollow boss *b* and an outwardly extending hollow boss *b'*, through which extends the platen shaft C. The plate or head B is secured in position on the end of 20 the platen by screws *b*², extending through screw holes *b*³, and such head is provided with holes *d* (Fig. 2) through which extend pins D which slide therein and are headed on their inner ends and are free to move in 25 recesses *d'* formed in the body of the platen and which recesses also house springs *d*² which are held in proper alinement by reduced extensions X of the pins D and serve to press the pins outward. The platen shaft 30 is formed with a longitudinal channel or bore *c* connecting with a longitudinal slot *c'* extending from the outer end of the shaft inward to the head B. The spring-pressed pins D are secured at their outer ends to a 35 locking member E which surrounds the boss *b'* and is free to slide thereon. Said locking member is here shown in the form of a circular plate or disk and it is provided with a tongue *e* which enters the slot *c'*. The disk 40 E may be formed with a single continuous flange or rim, or as shown formed with one or more, preferably three, outwardly extending flanges *e'* which preferably incline slightly inward toward the axis of the disk 45 and on the outside of these flanges are formed fine teeth or ridges, as indicated at *e*². The other locking member F is preferably in the form of a cup, surrounding the boss *b'* and also surrounding the locking 50 member E. Said cup-shaped member F is loose on the platen shaft, *i. e.*, it does not turn therewith unless held by the locking member E which does at all times turn with the platen, as before stated. On the inside 55 of the rim of the member F there is an annular series of horizontally disposed fine teeth or ridges *f* which are adapted to interlock with the teeth *e*² of the member E. When so gradually engaged the two members 60 are locked and turn together. Formed on, a part of, or firmly attached to the member F is the line-spacing ratchet wheel G which may be operated by any suitable mechanism in the usual way. The mechanism 65 is suitably supported by means of

frame parts H connected to, or forming part of, the carriage frame.

The hand wheel or twirler I is provided with a hub *i* secured rigidly at *i'* to the platen shaft. This hub is recessed, as shown, 70 to receive the hub or boss *k* of the push button K. Said boss is formed with a peripheral groove *k'* into which extends a screw *l* carried by the hub *i* and to the boss *k* is attached a rod L which contacts with the 75 tongue *e* of the locking member E. The rod may be moved endwise in the platen shaft C to the extent indicated, its inward movement being limited by the contact of the hub *i* with the end of the shaft C and its 80 outward movement being limited by the contact of the screw *l* with the inner end wall of the groove *k'*. The teeth or ridges *e*² and *f* on the locking members are necessarily made of minute divisions so that a very fine 85 adjustment may be obtained and these teeth or ridges are preferably of the form shown on an enlarged scale in Figs. 7 and 8. By reference to Fig. 7 it will be seen that the teeth or ridges in the locking members are 90 engaged by a graduated action inasmuch as the flanges *e'* are slightly inclined so that when the member E approaches the member F the teeth or ridges on the locking members are freely and gradually engaged with 95 each other and are then firmly locked. This is an important feature of my invention. It enables me to use fine teeth or ridges so that very fine adjustments may be obtained and yet the teeth or ridges when engaged are 100 so firmly locked that any false movement or slipping of the parts is entirely avoided.

My improvements, as before stated, may be used in connection with any suitable line-spacing mechanism. In Fig. 9 I have shown 105 mechanism of this kind of the form more fully illustrated and described and claimed in my application for Patent No. 863,264 filed Sept. 24, 1914. Briefly stated this mechanism comprises a lever M actuating a 110 push pawl N engaging the ratchet wheel G before referred to, a shield O partially surrounding the ratchet wheel for determining the number of teeth exposed to the action of the pawl. The mechanism shown also comprises a lever P moved in one direction by a 115 spring *p* and carrying a spring *R* equipped with a roller pawl or dog *q* which acts as a detent and also as a means for turning the wheel backward when desired. The spring 120 *R* attached to the lever P normally holds the pawl *q* in engagement with the ratchet wheel but said pawl may be withdrawn from the ratchet by means of a cam S actuated by an operating lever T. If desired 125 the exponent device, its lever P and spring *p* may be omitted when the spring holding block Z, carried by the lower end of the lever P, may be secured to the carriage end plate. It will thus be understood that my 130

improvements may be used in connection with mechanism for line spacing without in any way interfering with its normal operation.

5 The locking members are normally engaged with each other in the manner indicated in Fig. 1 and then the ratchet wheel is firmly connected with the platen and the latter may be operated by the line spacing devices in the usual way. But when it is desired to adjust between the lines or to print at some particular part of a sheet to which the line spacing mechanism is not adapted to adjust the push button K is 10 moved inward in the manner indicated in Fig. 6 so as to disengage the locking member E from the member F. At this time the platen is not operatively connected with the ratchet wheel and the platen may, by 15 means of the hand wheel I, be turned in either direction to any extent permitted by the minute graduations e^2 on the flanges e' coacting with the fine teeth or ridges f on the inside of the member F. As soon as 20 pressure is removed from the push button the member E moves into engagement with the member F and the platen is firmly locked in position and the printing at the adjusted line of print may be effected and 25 this may be done without disturbing to any appreciable extent the adjustment because the teeth or ridges on the locking members are very fine and these fine teeth or ridges are made to securely interlock with each 30 other by reason of the fact that as indicated in Fig. 7 they gradually engage each other without materially disturbing the platen adjustments and yet such engagement is easily accomplished and when perfected is most 35 accomplished and when perfected is most 40 secure.

The ridges or fine teeth on both members of the locking device are of considerable length as compared with their width and the longitudinal edges of the ridges on one 45 member are inclined relatively to the longitudinal edges of the ridges on the other member so that when one member is moved toward the other the ridges on one member gradually enter the grooves between the 50 ridges on the other member and the two sets of ridges finally become firmly engaged with each other. By this construction I am able to use a very large number of extremely narrow or fine ridges and grooves 55 and thus obtain an exceedingly fine adjustment and am able to cause the members to readily engage without danger of their slipping past each other.

I claim:

60 1. Platen release mechanism for typewriting machines comprising, in combination with the platen and its shaft, a ratchet wheel and locking members for connecting the ratchet wheel with the platen having 65 fine interlocking ridges which have their

longitudinal or peripheral edges inclined relatively to each other.

2. Platen release mechanism for typewriting machines comprising, in combination with the platen and its shaft, a ratchet 70 wheel and locking members for connecting the ratchet wheel with the platen having interlocking fine ridges which have their longitudinal edges inclined relatively to each other and have their engaging or contacting portions of the same width.

3. Platen release mechanism for typewriting machines comprising, in combination with the platen and its shaft, a ratchet wheel and locking devices for connecting 80 the ratchet wheel with the platen shaft consisting of two members one of which is connected to rotate with the platen and the other with the ratchet wheel both of said members being provided with interlocking 85 ridges the longitudinal edges of the ridges on one member being inclined relatively to the longitudinal edges of the ridges on the other member, the contacting or engaging portions of the ridges on one member being 90 of the same width as the corresponding parts on the other member.

4. Platen release mechanism for typewriting machines comprising, in combination with the platen and its shaft, a cup-shaped locking member connected to rotate with the ratchet wheel and having on the inside of its rim a circular series of diminutive ridges, a flanged locking member connected to move with the platen and having 95 ridges on said flange engaging the ridges on the cup-shaped member, the longitudinal or peripheral edges of which are set at an angle to the longitudinal edges of the 100 ridges on the cup-shaped member.

5. Platen release mechanism for typewriting machines comprising, in combination with the platen and its shaft, a ratchet wheel loose on the platen shaft and locking members for connecting the platen with the ratchet wheel, one of which members is formed with fine ridges the longitudinal edges of which are parallel with the axis of the platen and the other of which members is formed with fine ridges the longitudinal 110 edges of which are set at an angle to the longitudinal edges of the ridges on the first mentioned locking member, said ridges in both members being of the same width 115 where they engage or contact with each 120 other.

6. Platen release mechanism for typewriting machines comprising, in combination with the platen and its shaft, a ratchet wheel loose on the platen shaft, a locking 125 member connected with the ratchet wheel to rotate therewith and which is provided with interlocking ridges, a locking member connected to rotate with the platen and having ridges adapted to engage the ridges on 130

the other locking member, spring pressed pins housed in the platen and tending to hold the locking members in engagement with each other and a push rod mounted to slide centrally in the platen shaft and directly engaging one of said members for separating it from the other member.

In testimony whereof, I have hereunto subscribed my name.

EDWARD B. HESS.
